Inventor

Dear Mr. Hardy.

UNITED STATES PATENT OFFICE.

IRA KINCAID, OF CHICAGO, ILLINOIS, ASSIGNOR OF ONE-THIRD TO WARREN H. NEUREITHER AND ONE-THIRD TO MARK A. FOOTE, BOTH OF CHICAGO, ILLINOIS.

BRAKE-SHOE FOR RAILROAD-CARS.

1,025,916.

Specification of Letters Patent. Patented May 7, 1912.

Application filed August 19, 1910, Serial No. 577,993. Renewed April 11, 1912. Serial No. 690,001.

To all whom it may concern:

Be it known that I, IRA KINCAID, a citizen of the United States, residing at Chicago, in the county of Cook and State of Illinois, have invented certain new and useful Improvements in Brake-Shoes for Railroad-Cars, of which the following is a specification.

My invention relates to brake shoes for railroad cars and particularly for railroad locomotives, and the object of the invention is to provide means whereby the flange of a locomotive or car wheel may be kept lubricated, thus preventing the rapid cutting away of the flange when running on curves, the wearing away of the rail and very much reducing the danger of derailment, as it is the worn flanges of the car wheels and the worn rails that are apt to cause such derailments, particularly at switches.

The invention consists in its general features in a brake shoe formed with a pocket, the pocket opening upon the flange groove of the shoe and being filled with oil-soaked waste or other lubricant so that the lubricant in the pocket will be applied to the inside face of the flange of the wheel, thus rendering the inside face of the flange oily and lubricating the surface which ordinarily comes in contact with the rails of a track particularly when the train is going around a curve. The constant grinding of the flange particularly when the car is moving upon curves tends to wear away the flange, destroying the usefulness of the wheel and also wear away the rails, particularly at the switches.

One form of my invention is shown in the accompanying drawings wherein:

Figure 1 is a fragmentary side elevation of a portion of the locomotive wheel and the brake head and brake shoe applied thereto, my improvement in the brake shoe being shown in dotted lines. Fig. 2 is a transverse section on the line 2-2 of Fig. 1. Fig. 3 is an inside face view of the brake shoe.

Referring to these figures, 2 designates a car wheel of any suitable character shown as the wheel of a locomotive, this wheel being formed with the usual flange 3. The brake head 4 is of any ordinary or usual construction and is shown as being formed with a socket 5 at its upper end and with a recess 6 at its lower end, the socket and recess being provided for the purpose of attaching

the brake shoe 7 to the head. The interior face of the head 4 is concave and the shoe is longitudinally concavo-convex, fitting of course the curvature of the wheel.

The shoe proper 7 is of any usual or ordinary form and as shown is provided at its upper end with a hook-like portion 8 which is adapted to be received in the recess or socket 5 and at its lower end is provided with a bolt 9, the head of which is sunk in the face of the brake shoe, and the end of which extends through the opening 6 in the head and is held in place by means of a cotter pin 10 or in any other suitable manner. The construction above described is that common to a large variety of brake shoes and is not part of my invention.

My invention consists in providing the brake shoe with a longitudinally extending pocket 11 which is formed by coring the brake shoe, this pocket being about three inches long and one and a half inches square. The pocket is provided on its upper end with a duct 12 which leads to the upper end of the brake shoe and may be provided with any suitable plug whereby the duct may be closed if desired. The pocket 11 has a peculiar relation to the flange groove 13 which is formed in the face of the brake shoe to accommodate the flange 3. As shown in Fig. 3 the pocket opens along its entire length upon the inside face of the flange groove so that the waste or other suitable lubricant carried within the pocket will come in contact with the inside face of the flange. The pocket in cross-section is gradually contracted toward its opening as shown in Fig. 3, so as to prevent the lubricant contained in the pocket from being pulled out by any roughness in the face of the wheel flange. One wall of the pocket intersects the flange groove at a point slightly inward from the face of the brake shoe, while the other side wall of the pocket intersects the flange groove at a point approximately at the bottom of the groove, as illustrated in Fig. 2. The pocket is to be filled with waste such as ordinarily used for lubricating purposes or with other lubricant such as grease, and it will be obvious that the lubricant will contact with the inner face of the flange 3 and that the lubricant such as the oil absorbed by the waste will be distributed over the inner face of the flange.

It will be noted that there is practically the

same pressure upon the oily waste at all times whether the brake shoe is at rest or in operation, the pressure depending upon the consistency of the waste as packed in the pocket.

In the ordinary running of the train the flange 3 will constantly wipe against the oily waste contained in the pocket and the inner face of the flange will be constantly kept lubricated so that when the inner face of the flange comes in contact with a rail as in rounding a curve, the contacting faces of the flange and rail will be lubricated and thus there will be much less friction between the flange and the rail. This lubrication of the contacting faces of flange and rail will tend to reduce the power necessary to draw the train, and furthermore will reduce wear of the flange and rail and prevent their being laterally cut away.

While I have shown my invention as applied to a brake shoe and rail of an ordinary form, I do not wish to be limited to this form as it is obvious that the invention might be embodied in other forms of brake shoe.

What I claim is:

A concavo-convex brake shoe for vehicle wheels having a flange receiving groove in the concave face thereof near one longitudinal edge of the shoe and opening through the top and bottom of said shoe, there being

a longitudinally curved pocket formed in the body of the shoe at the rear of the groove and of less length than the latter, said pocket being disposed at an angle to one longitudinal edge of the shoe and having its side walls unobstructed and converged in the direction of the flange receiving groove to form a contracted mouth opening through one side wall of said flange receiving groove and terminating short of the other, there being a vertically disposed duct of less cross sectional diameter than the pocket opening through the top of the shoe in spaced relation to the grooved face thereof and communicating with said pocket to permit the introduction of a lubricant, said duct being disposed in vertical alinement with and forming a continuation of the longitudinally curved rear wall of the pocket, and a detachable plug seated in the upper end of the duct and forming a closure for the latter, that portion of the concave face of the shoe between the flange receiving groove and the other longitudinal edge of said shoe being of the same width as and adapted to bear against the periphery of the wheel.

In testimony whereof I affix my signature in presence of two witnesses.

IRA KINCAID. [L. S.]
